UNITED STATES PATENT OFFICE.

ROBERT SCOTT, OF NOTTINGHAM, ENGLAND.

JACQUARD MECHANISM FOR EMBROIDERING-MACHINES.

SPECIFICATION forming part of Letters Patent No. 610,248, dated September 6, 1898.

Application filed March 31, 1898. Serial No. 675,967. (No model.)

To all whom it may concern:

Be it known that I, ROBERT SCOTT, lace-draftsman, a subject of the Queen of Great Britain, residing at 37 Birrell road, Sherwood 5 Rise, Nottingham, England, have invented certain new and useful Jacquard Mechanism for Embroidery-Frames, of which the following is a specification.

The object of this invention is to apply 10 jacquard mechanism to give the to-and-fro and up-and-down motions to an embroidery-frame.

Figures 1 and 2 are front elevations of the 15 left and right hand portions of the machine, Fig. 2 being to half the scale of Fig. 1. Fig. 3 is a horizontal section on the lines 3 3, Figs. 1 and 2. Fig. 4 is a vertical section on the line 4 4, Figs. 1 and 3. In the figures the greater 20 part of the framing is omitted for the sake of simplicity.

a is the embroidery-frame, which has fixed to it rails *a'* free to run on grooved pulleys *b'*, carried by levers *b*, pivoted at *b'*. The other ends of the levers *b* are pivoted to a 25 counterbalance-weight *c*.

c' is a rod fixed to the weight *c* and carrying grooved rollers *c'*, running on the diagonal bar *d'* of the frame *d*, which is free to be moved horizontally to and fro in fixed bearings *d'* by the bar *A*, to which motion is given, as hereinafter described.

If the bar *A* and frame *d* are pushed to the right, the weight *c* is raised and the frame *a* is lowered, whereas if the bar *A* is pulled to 35 the left the frame *a* is raised.

The to-and-fro horizontal movement is given to the frame *a* by the bar *B*, whose end carries a rack gearing with the toothed wheel *e*, fixed to the shaft *e'*, on which is a feather *e'*.

f is a pinion gearing with a rack *a'*, fixed 40 on the frame *a* and free to slide on the shaft *e'*, but turning with it, being grooved to fit the feather *e'*. As the bar *B* moves to and fro, therefore, the frame *a* moves with it, but to a diminished extent.

Motion is given to the bars *A* and *B* in the following manner.

g is a shaft revolving once for every stitch and having fixed to it four equal and similar 50 cams *g' g' g' g'*. The cams *g' g'* and *g' g'*, respectively, are similarly placed on the shaft.

These cams act on rollers *h' h'* on four slides *h*, to which they give a to-and-fro motion. The slides *h* have pivoted to them connecting-rods *h'*, whose other ends are pivoted to links 55 *j*, the latter being also pivoted at *j'* to levers *k*, which are pivoted at *k'*.

C is a bar free to move longitudinally in bearings. Each link *j* passes through a hole in the bar *C* between two knife-edges *C'*, fixed 60 to it. Each lever *k* is acted on by a multiple lift jacquard of ordinary construction.

l is a grid which reciprocates up and down through the same distance every stitch.

l' is a frame connected by the rod *l'* to the 65 lever *k*.

l' are vertical needles pivoted to the top bar of the frame *l'* and pulled to one side or left in the path of the grid by the jacquard-needles in the ordinary way.

As the grid *l* rises the frame *l'* remains stationary unless and until the grid comes against one or other of the needles *l'* which has not been pulled aside by the jacquard, and the frame *l'* is then lifted by the grid during the remainder of the stroke of the latter, so raising the lever *k* and link *j* more or less, according to which of the needles *l'* is engaging with the grid. The link *j* is oscillated about its pivot *j'* by the rod *h'*, causing the rod 70 *C* to move to and fro, the extent of its reciprocations depending on the height to which the pivot *j'* has been raised. The jacquard-cards are so punched that only one at the most of the levers *k* of each pair is raised at any 75 time, as shown at Fig. 4.

The bars *C* have teeth or racks *C'* at one side of their ends, and the bars *A* and *B* have similar teeth or racks *A' B'* on both sides. Normally the teeth on the bars *C* do not engage 80 with those on the bars *A* and *B*, but when one of the levers *k* is raised by the jacquard, as above described, the recess *k'* in the plate *k'* is lifted above the ball *C'*, (carried by the bar *C*), so that the side of the plate *k'* is now 85 in contact with the ball, as shown at Fig. 4.

g' are projections on the side of the cam-disks *g' g' g' g'*, and as the cams revolve these projections acting on any of the plates *k'* which are raised press them sidewise against the 90 bars *C*, putting the teeth of the latter into gear with the teeth on the bar *A* or *B*, as the case 95

may be, causing this bar to move with the bar C, and thus giving the required vertical or horizontal movements to the embroidery frame.

5 What I claim is—

1. The combination of a frame, two parallel bars free to move longitudinally, mechanism actuated by the bars moving the frame in two directions at right angles to each other, 10 second and third pairs of parallel bars, means whereby one or other bar of each of the latter pairs moves one of the first bars and pattern mechanism reciprocating the second and third pairs of bars.

15 2. The combination of a frame, a diagonal guide, a part moving in the guide and connected to the frame, two parallel bars free to move longitudinally, connections between one bar and the frame and the other bar and the 20 guide, pattern mechanism and means actuated by it for moving the bars.

25 3. The combination of a frame, two parallel bars free to move longitudinally, a diagonal guide, a part moving in the guide, connections between one bar and the frame and the other bar and the guide, second and third pairs of parallel bars, means whereby one or other bar of each of the latter pairs moves one of the first bars, and pattern mechanism 30 reciprocating the second and third pairs of bars.

35 4. The combination of a frame, two parallel bars free to move longitudinally, mechanism actuated by the bars moving the frame in two directions at right angles to each other, second and third pairs of parallel bars, means whereby one or other bar of each of the latter pairs moves one of the first bars, jaws on the bars of the second and third pairs, links 40 passing between the jaws, rods pivoted to one end of the links, means for reciprocating the rods through a constant distance, levers pivoted to the other ends of the links, and pattern mechanism for raising the levers.

45 5. The combination of a frame, two parallel bars free to move longitudinally, a diagonal guide, a part moving in the guide, connections between one bar and the frame and the other bar and the guide, second and third pairs of parallel bars, means whereby one or other bar of each of the latter pairs moves one of the first bars, jaws on the bars of the second and third pairs, links passing between the jaws, rods pivoted to one end of the links, means for reciprocating the rods through a constant distance, levers pivoted to the other ends of the links, and pattern mechanism for 55 raising the levers.

60 6. The combination of a frame, two parallel bars free to move longitudinally, mechanism actuated by the bars, moving the frame in two directions at right angles to each other, second and third pairs of parallel bars, teeth on two sides of the bars of the first pair, teeth 65 on one side of the other bars, means whereby the latter teeth are caused to engage with the

former, and pattern mechanism reciprocating the second and third pairs of bars.

7. The combination of a frame, two parallel bars free to move longitudinally, a diagonal guide, a part moving in the guide, connections between one bar and the frame and the other bar and the guide, second and third pairs of parallel bars, teeth on two sides of the bars of the first pair, teeth 75 on one side of the other bars, means whereby the latter teeth are caused to engage with the former, and pattern mechanism reciprocating the second and third pairs of bars.

8. The combination of a frame, two parallel bars free to move longitudinally, mechanism actuated by the bars moving the frame in two directions at right angles to each other, second and third pairs of parallel bars, teeth 80 on two sides of the bars of the first pair, teeth on one side of the other bars, means whereby the latter teeth are caused to engage with the former, jaws on the second and third pairs of bars, links passing between the jaws, rods pivoted to one end of the links, means for 85 reciprocating the rods through a constant distance, levers pivoted to the other ends of the links, and pattern mechanism for raising the levers.

9. The combination of a frame, two parallel bars free to move longitudinally, a diagonal guide, a part moving in the guide, connections between one bar and the frame and the other bar and the guide, second and third pairs of parallel bars, teeth on two sides of 90 the bars of the first pair, teeth on one side of the other bars, means whereby the latter teeth are caused to engage with the former, jaws on the second and third pairs of bars, links passing between the jaws, rods pivoted 95 to one end of the links, means for reciprocating the rods through a constant distance, levers pivoted to the other ends of the links, and pattern mechanism for raising the levers.

10. The combination of a frame, two parallel bars free to move longitudinally, mechanism actuated by the bars moving the frame in two directions at right angles to each other, second and third pairs of parallel bars, jaws on the bars of the second and third pair, links 100 passing between the jaws, rods pivoted to one end of the links, means for reciprocating the rods through a constant distance, levers pivoted to the other ends of the links, pattern mechanism for raising the levers, plates 105 on the levers, teeth on two sides of the bars of the first pair, teeth on one side of the other bars, and cams acting on the plates when raised, causing them to move the bars of the second and third pairs, so making their teeth 110 engage with those of the first bars.

11. The combination of a frame, two parallel bars free to move longitudinally, a diagonal guide, a part moving in the guide, connections between one bar and the frame and the other bar and the guide, second and third pairs of parallel bars, jaws on the bars of the 115

second and third pairs, links passing between the jaws, rods pivoted to one end of the links, means for reciprocating the rods through a constant distance, levers pivoted to the other ends of the links, pattern mechanism for raising the levers, plates on the levers, teeth on two sides of the bars of the first pair, teeth on one side of the other bars,

and cams acting on the plates when raised, causing them to move the bars of the second and third pairs, so making their teeth engage with those of the first bars.

ROBERT SCOTT.
